PETROL SUPPLY PUMPING MECHANISM FOR
INTERNAL COMBUSTION ENGINESWilliam Cull, Shipley, England, assignor to Scott
Motors (Saltaire) Limited, Shipley, EnglandApplication December 28, 1939, Serial No. 311,401
In Great Britain July 6, 1938

4 Claims. (Cl. 137—165)

This invention relates to pumps of the diaphragm or bellows type commonly used upon internal combustion engines for pumping petrol to the carburetor, and in which the diaphragm or bellows, hereinafter termed "diaphragm," during its positive suction stroke draws petrol through an inlet valve into a chamber and during the delivery stroke, usually under spring pressure, forces it through a non-return outlet valve to the carburetor. The chief object of the present invention is to provide a pump of this type which will be adapted to pump liquids, say of different viscosities such for example as petrol and oil, in predetermined proportions and deliver them mixed together to the carburetor.

According to the invention the pump diaphragm has connected thereto a means adapted to inject into the chamber or other space a predetermined quantity of oil at each stroke of the diaphragm. This means is preferably of hollow construction and provided with a valve so that at each stroke of the diaphragm said means delivers a predetermined quantity of oil into the petrol drawn into the chamber by the diaphragm. Preferably means are also provided for agitating the oil and petrol in the chamber to ensure their thorough mixing.

In one form of the invention the ratio of the quantities of petrol and oil delivered into the chamber will be in accordance with the relative volumetric displacement of the diaphragm and said injecting means, or in accordance with the relation between their effective areas when their strokes are the same.

In order that the invention may be clearly understood and readily carried into effect, the same will now be more fully described with reference to and by the aid of the embodiments illustrated in the accompanying drawings, wherein:

Figure 1 is a part sectional elevation of a pumping mechanism.

Figure 2 is a similar view to Figure 1 but illustrates a modified form of pumping mechanism.

Figure 3 is a sectional detail view of the vane and its tubular support.

Figure 4 illustrates an alternative construction.

Referring to Figure 1 of the drawings, the pump consists of a diaphragm 1 mounted in a casing 2 which may be secured to the engine (not shown). The casing 2 affords a receiving and discharging chamber 3 which will be provided with an inlet passage 30 in which is mounted a non-return inlet valve, through which petrol

or other liquid is introduced into the chamber 3. The casing also has an outlet passage 31 in which is mounted a non-return outlet valve, through which the mixture in the chamber 3 is discharged. The openings 30 and 31 and the valves 5 therein are preferably situated diametrically opposite one another with the petrol inlet opening 30 at the lowest point in the discharge chamber 3 and with the mixture outlet opening 31 vertically opposite or at the top of said chamber 3 so that any oil which, due to separation, collects when the pump has stood inactive for any period will be in the direct line of the stream of petrol when the pump is started up, and since this stream has a comparatively high velocity it 15 assists in producing a uniform mixture at the initial period of running. The diaphragm 1 is directly connected to the operating means, which in this form of the invention constitutes a pump plunger 4 mounted in the pump casing 2, said plunger 4 being reciprocated by any suitable means, such as a bell crank lever or rocker arm 5 operated by a cam 6 driven by the engine (not shown). A helical spring 7 of suitable tension abuts against the diaphragm 1 and the fixed casing 2 so that whilst the diaphragm 1 is positively operated on the suction stroke, the actual delivery head from the diaphragm can be controlled by suitable return spring pressure. 30

The operating plunger 4 is hollow at 11 and is extended so as to work within a cylindrical bore afforded in the pump casing 2, said plunger 4 having a non-return inlet valve 8 at its free end, and in this latter connection the valve 8 35 comprises a spring-loaded ball 9 held against a restricted inlet 10 in the end of the extended plunger.

The working space 3a of the plunger pump has a valve controlled inlet connected to the usual oil supply of the engine (not shown) so that when the diaphragm 1 is operated and petrol is drawn into the chamber 3, oil is forced through the inlet 10, along the bore 11 of the pump plunger 4, and injected into the chamber 3. In order to ensure the agitation and thorough mixing of the two fluids in the chamber 3, a vane 12 is secured to that end of the operating plunger 4 which projects into the chamber 3, and the vanes on said disc 12 are preferably set at an angle of 50 approximately 40° so that the axial movement of the diaphragm 1 and plunger element 4 will be imparted to the vanes which in turn will impart to the fluids an alternative right and left hand swirling motion. Additional turbulence of 55

the fluids may be caused by arranging the oil delivery or injection ports 13 into the chamber 3 tangentially and so as to be opposed to the angular setting of the vanes on the disc 12 when the vanes move in one direction.

The diaphragm 1 is preferably backed up by a spring pressed inverted cup-shaped ring 14 which controls the actual displacement of the diaphragm 1 throughout its range of speeds. 10 In other words, the tension of the spring 14 co-acts with the spring 1 to oppose the inward movement of the diaphragm 1 when the latter is displaced and these springs coact to return the diaphragm to its normal position when the displacing pressure is released.

The diameter of the pump plunger 4 is such in relation to that of the diaphragm 1 that a suitable ratio of oil and petrol is supplied to and mixed in the chamber 3.

20 In the modified construction of pumping mechanism shown in Figure 2, in which like references to those in Figure 1 indicate like or analogous parts, oil is supplied from the engine under pressure from a primary pump (not shown) and this initial oil pressure is utilised to control and effect the actual delivery head from the diaphragm. The pumping means 4 is of hollow construction and at its free end is adapted to work within a cylindrical member 15 which is engaged by the rocker arm 5. Transfer ports or oilways 16 are formed in the cylindrical member 15 which are adapted to connect and disconnect the initial pressure oil supply ports 17 with and from the inlet ports 18 of the hollow means 4. The free end of the means 4 is hollowed out at 19 and open to the initial oil pressure supply so that the means 4 is forced to bear against the cylindrical member 15 and cause the latter to engage the rocker arm 5.

40 In Figure 2, the diaphragm is shown at the commencement of the delivery stroke of the diaphragm. The initial oil pressure acting upon the means 4 causes the diaphragm to commence delivery and at the same time bring the ports or 45 oilways 16 into register with the ports 11 of the fixed casing 2 and the inlet ports 18 of the free end of the means 4, thus allowing the oil to pass into the bore of the hollow plunger.

The rocker arm then commences to return the cylindrical member 15 and the latter engages and moves the means 4 so that petrol flows into the chamber and along the hollow means 4 through the ports 13 into the chamber 3 where the vaned disc 12 agitates and thoroughly mixes the petrol 55 and oil.

It will be seen that the pumping of the petrol by the diaphragm is entirely dependent upon the initial oil pressure being supplied to the means, so that in the event of the engine oil pump failing, the engine will not run owing to the stopping of the petrol pump.

Figure 4 shows an example of how variable ratios may be obtained by altering the relative strokes of the diaphragm and the oil pump plunger. The diaphragm is operated by a rocker arm 20 and the reciprocation of the former is transmitted to the oil pump plunger 4 through the medium of a pair of pivotally mounted levers 21 having between them an adjustable bowl or runner 28, operating in such a manner that when the latter is centrally placed, as shown in said figure, the effective lengths of the levers 21 and consequently the strokes of the diaphragm 3 and plunger 4 are equal and by adjusting the runner 28 to any eccentric position,

the effective length of one lever is increased as the other is decreased and vice versa, according to the direction of movement of the said runner 28, so that the stroke of the oil pumping plunger 4 is varied in relation to that of 5 the diaphragm.

I claim:

1. In a pumping arrangement of the type specified, the combination with the positively actuated diaphragm pump for pumping a liquid into 10 and from a chamber, of a plunger pump for pumping a second liquid into said chamber, a vaned disc in the latter which partakes of the movements of the diaphragm to impart swirling motion to the liquids to ensure thorough mixing, 15 a conduit connecting the working space of the plunger pump to the chamber, a non-return valve in said conduit, and an operative connection between the diaphragm and the plunger so that for each suction stroke of the diaphragm the 20 predetermined quantity of the first liquid is drawn into the chamber by the diaphragm and a predetermined quantity of the second liquid is injected into the chamber by the plunger, and that for each return stroke of the diaphragm the 25 two liquids mixed in their predetermined proportion, are forced from the chamber and a fresh charge of the second liquid enters the working space of the plunger pump.

2. In a pumping mechanism of the type specified, the combination with the positively actuated diaphragm pump for pumping a liquid into and from a chamber, of a means for controlling the flow of a second liquid into said chamber, which second liquid is supplied under pressure 35 to the means, a conduit formed through the means and connecting the working space of the means to the chamber, a non-return valve in said conduit, an operative connection between the means and the diaphragm, a cylindrical member 40 within which the free end of the plunger works, a positively operated actuating member which engages said cylindrical member, the initial pressure of the second liquid serving to keep the means in engagement with the cylindrical 45 member and cause the latter to follow the positively operated actuating member, inlet ports in the hollow means, and transfer ports in the cylindrical member adapted to connect and disconnect initial pressure liquid supply ports with 50 and from the means inlet ports according to the movement of the positively operated actuating member.

3. In a pumping mechanism of the class described, the combination with a casing having a 55 chamber therein, said casing being provided with valve controlled inlet and outlet openings, a positively actuated diaphragm for drawing a liquid into the chamber through said inlet opening, means for effecting the flow of a second liquid 60 into said chamber, said casing having a working space associated with said means, a passage communicating the working space with said chamber, a valve means associated with said means and passage for controlling the flow of 65 said second fluid so as to prevent its reverse flow, means for operating said means and said diaphragm in one direction so that when said diaphragm draws a predetermined quantity of liquid into said chamber, the first mentioned means 70 will effect the injection of a predetermined quantity of the second liquid into said chamber, means for moving said diaphragm and first mentioned means in the opposite direction, and means for agitating the mixture in said chamber, the move- 75

ment of the diaphragm in the last mentioned direction effecting the operation of the agitating means and the discharge of the mixture from the chamber.

5 4. In a pumping mechanism of the class described, the combination with a casing having a chamber therein, said casing being provided with valve controlled inlet and outlet openings, a positively actuated diaphragm for drawing a liquid 10 into the chamber through said inlet opening, a plunger for pumping a second liquid into said chamber, said casing having a working space associated with said plunger, said plunger having a passage therein communicating the working

space with said chamber, a non-return valve in said passage for controlling the flow of the second liquid therethrough, means for operating said plunger and said diaphragm in one direction so that when said diaphragm draws a predetermined quantity of liquid into said chamber, the plunger will effect the injection of a predetermined quantity of the second liquid into said chamber through said passage, and means for moving said diaphragm and plunger in the opposite direction, the movement of the diaphragm in the last mentioned direction effecting the discharge of the mixed liquids from the chamber. 5 10

WILLIAM CULL.
